(57) **CLAIM**

The ornamental design for an apparatus for un-locking security device for retail merchandise, as shown and described.

DESCRIPTION

Article for un-locking and facilitating removal of an anti-theft device from merchandise sold in retail channels of trade.

FIG. 1 is an isometric illustration of an apparatus for un-locking security device for retail merchandise, showing the new design;

FIG. 2 is a side elevation view of the article of FIG. 1, the opposing side being a mirror image of the side shown;

FIG. 3 is a top plan view of the article of FIG. 1;

FIG. 4 is a front elevation view of the article of FIG. 1;

FIG. 5 is a rear elevation view of the article of FIG. 1;

FIG. 6 is a bottom plan view of the article of FIG. 1;

FIG. 7 is an isometric view of the article of FIG. 1, with the retractable cover disposed in a closed condition;

FIG. 8 is a side elevation view of the article of FIG. 1 in the closed condition illustrated in FIG. 7, the opposing side being a mirror image of the side shown;

FIG. 9 is a top plan view of the article of FIG. 1 in the closed condition illustrated in FIG. 7;

FIG. 10 is a front elevation view of the article of FIG. 1 in the closed condition illustrated in FIG. 7;

FIG. 11 is a rear elevation view of the article of FIG. 11 in the closed condition illustrated in FIG. 7; and,

FIG. 12 is a bottom plan view of the article of FIG. 1 in the closed condition illustrated in FIG. 7.
